DESIGN FOR DOG GOGGLES

James E. Guernsey, West Roxbury, Mass., assignor to Polaroid Corporation, Cambridge, Mass., a corporation of Delaware

Application August 23, 1943, Serial No. 110,979

Term of patent 3½ years

(Cl. D38—6)

To all whom it may concern:

Be it known that I, James E. Guernsey, a citizen of the United States, residing at 37 Pomfret Street, West Roxbury, in the county of Suffolk and State of Massachusetts, have invented a new, original, and ornamental Design for Dog Goggles, of which the following is a specification, reference being had to the accompanying drawing, forming part thereof.

Figure 1 is a front elevational view of dog goggles, showing my new design; and

Figure 2 is a side elevational view thereof.

I claim:

The ornamental design for dog goggles, substantially as shown.

JAMES E. GUERNSEY.
